FUEL SUPPLY SYSTEM FOR BURNERS

Ervin H. Mueller, Grosse Pointe Park, Mich.

Application August 30, 1940, Serial No. 354,910

2 Claims. (Cl. 158—117.1)

This invention relates to an arrangement involving controlling valves for supplying fluid fuel to burners.

The invention is concerned particularly with the provision of an arrangement for supplying gaseous fuel in installations commonly used in mild climates where the so-called floor burners are employed. In my application Serial No. 346,739, filed July 22, 1940, a control valve for a floor burner is disclosed, and a valve of this nature can be employed in the present system. The floor burner is an arrangement usually suspended from the ground floor for burning gaseous fuel, and the control is effected by the operation of valves from above the floor. The general object of the invention is to provide an improved arrangement and system embodying but two control valves for controlling the flow of fuel to the burner and pilot, and also for preventing escape of gaseous fuel in the event the pilot flame becomes extinguished, but wherein the pilot flame may be temporarily supplied with gas for re-ignition.

An arrangement for carrying out the invention is disclosed in the accompanying drawings.

Fig. 1 is a plan view of a system or lay-out for carrying out the invention.

Fig. 2 is an enlarged cross sectional view taken through the main control valve substantially on line 2—2 of Fig. 1.

Fig. 3 is a similar enlarged cross sectional view taken on line 3—3 of Fig. 1.

Fig. 4 is a cross sectional view of the control valve for the pilot flame.

Fig. 5 is a view similar to Fig. 4 showing a modified form of pilot control valve.

Fig. 6 is a cross sectional view taken substantially on line 6—6 of Fig. 2 through the cap of the main control valve showing different positions of the valve.

Fig. 7 is a sectional view taken substantially on line 7—7 of Fig. 2 showing positions corresponding to the Fig. 6 positions.

Fig. 8 is a sectional view taken substantially on line 8—8 of Fig. 2 showing a position corresponding to that of Figs. 6 and 7.

Fig. 9 is a cross sectional view similar to Fig. 8 illustrating another position as indicated by the dotted lines of Figs. 6 and 7.

Fig. 10 is a cross sectional view similar to Fig. 6 illustrating other positions of the control valve.

Fig. 11 is a view similar to Fig. 7 showing the positions of the main fuel supply corresponding to the positions shown in Fig. 10.

Fig. 12 is a view similar to Fig. 8 illustrating

the pilot flow ports corresponding to the positions shown in Figs. 10 and 11.

Fig. 13 is a view similar to Fig. 12 illustrating another position of the pilot flow ports.

In Fig. 1 a gas supply line is shown at 1 for supplying gas to a burner 2 and in the line is a thermostatically controlled shut-off device or valve diagrammatically illustrated at 3 controlled by a thermocouple lead 4 subject to the pilot flame. Another automatically acting and thermostatically controlled valve or shut-off device is shown at 5, while the main valve for the burner is generally illustrated at 6. A conduit 7 for the gaseous fuel for the pilot by-passes the thermostatic device 5, enters the main valve as at 8 and passes out at 9 through a pilot starter valve 10 and through line 11 to the pilot burner 12, the flame of which is illustrated at 13. It will be noted that the thermocouple lead 4 is positioned to be heated by the pilot flame. An auxiliary gas supply by-passes both the thermostatically acting valves 3 and 4 as by means of conduit 15 entering the valve 10 as at 16.

The valve 10, as shown in Fig. 4, has a chamber 20 closed by a cap 21, and the line sections 9 and 11 are connected directly through this chamber. The inlet and outlet ports are shown at 19 and 22. The line 15 enters into a passage 23 which is closed by a disc valve 24 acted upon by a spring 25. A pin 26 connects to the disc valve and is slidably positioned in the body 10 and is provided with a cap 29. A spring 27 may surround the pin and also serves to close the valve 24, and the pin may pass through a suitable packing 28. The valve 24 and packing 28 may be of rubber or synthetic rubber.

The main valve 6 has a tapered valve plug 31 with a port 31 therethrough for completing the main supply line. The plug also has a passage 32 for the pilot fuel which passes through the plug at right angles to the passage 31, and as best shown in Fig. 8 the ends of the passage are provided with arcuate grooves 33. The valve may be held upon its seat by a spring 34.

The control for the valve is the same as that shown in my prior application above mentioned and has a stem 40 non-rotatably fixed to the valve member by a pin and slot connection 41. A cross pin 42 lies in a transverse slot in the valve member, and it is held upwardly against cap 43 by a spring 44 reacting on a washer 45.

The valve cap is fashioned with stops for the pin 42 which limits the rotary movements of the valve member. When the valve is open as shown in Fig. 2 the ends of the pin abut the limiting

stops 50 and 51 as shown in Fig. 6. When the valve is turned off the pin abuts stops 52 and 53 as shown by the dotted lines. In the full "on" position, as shown by the full lines in Fig. 6, the by-pass 32 lines up with the fuel supply line as shown in Fig. 8. When the main supply is turned off by positioning the valve as shown in Fig. 7, fuel is supplied to the burner through the passage 32 and the arcuate slots as shown in Fig. 9. Thus the burner may be turned off and on while gas is supplied to the pilot. This is the normal condition during the operating period. The stops 52 and 53 do not extend all the way down to the valve body as shown in Figs. 2 and 3, with the result that the cross pin 42 may be pushed downwardly against the action of the spring 44 by the rod 40, and then the valve turned to position the cross pin on the opposite sides of the stops 52 and 53 as shown in Fig. 10. With the pin abutting against stops 50a and 51a, as shown in Fig. 10, then both the main supply of fuel and the pilot supply of fuel is turned off, as illustrated in Figs. 11 and 12. This is the normal complete "off" position for the long season when no heat is required. When the valve is turned to position the cross pin against the stops 52 and 53, as shown by the dotted line position of Fig. 10, then fuel for the pilot is supplied through the arcuate passages and passage 32, as these passages are then in the position shown in Fig. 13.

Accordingly, in warm weather the main control valve 8 may be in the position shown in Figs. 10, 11 and 12 whereby both the main and pilot fuel lines are closed. By turning the valve to the dotted line position shown in Fig. 10, the pilot may be ignited. Then during the operating season the valve may be positioned so that the pin operates between the stops shown in Fig. 6, with the main burner off when the cross pin is against the stops 52 and 53, and on when the cross pin is against the stops 50 and 51, but with the pilot flame supplied with fuel at all times.

If the pilot flame becomes extinguished for any reason the gas supply would normally escape therefrom, but the thermocouple lead 4 causes the thermostatic valve 3 to close, thus cutting off the normal supply of fuel for the pilot. Under this condition fuel is supplied to the valve 10 through the line 15 but it is closed by the valve 24. An operator may push on the cap 29 to open the valve 24 to thus supply fuel to the pilot for its ignition, and when the heat therefrom has caused the thermostatic valve 3 to open, the cap 29 may be released to close valve 24 and the pilot fuel is supplied in the usual manner. Thus, a single valve and a single conduit to the pilot (the conduit 11) furnishes the normal fuel for the pilot flame and the auxiliary temporary fuel to ignite the pilot flame. The valve 24 must be opened to initially ignite the pilot flame at the start of the operating season.

A modified form of starter valve is shown in Fig. 5 where the same reference characters are

used with the addition of the letter *a*. This valve is of the same basic structure as the valve shown in Fig. 4, but instead of a sealing disc or washer 24, it is provided with a tapered valve plug member 24a arranged to seal against a tapered seat 55. When the tapered plug is on the seat the passage 23a is closed. When it is pushed off its seat by depressing the cap 29a, the auxiliary gas line through the passage 23a is open, which is the position shown in Fig. 5.

I claim:

1. In a fuel supply system for a burner of fluid fuel, the combination of a fuel supply line, a burner, a pilot burner, a main control valve in the supply line for controlling the supply of fuel to both the said burner and pilot burner, there being a single conduit for supplying fuel to the pilot burner, a thermally controlled shut-off valve positioned in the supply line upstream from the control valve and operated from the heat of the pilot flame, whereby, when the pilot flame is extinguished, the thermally controlled valve closes, a starter valve between the main valve and the said single conduit for the pilot burner, and which is normally open for the passage of fuel from the control valve to the pilot burner, a second conduit connecting into the supply line upstream of said thermally controlled valve and leading into the starter valve, said starter valve having passage means for connecting the second conduit with the said single conduit, means normally closing said passage, and means operable to open said passage for the supply of fuel to the pilot burner subsequent to the closing of the thermally controlled valve.

2. In a fuel supply system for a burner of fluid fuel, the combination of a fuel supply line, a burner, a pilot burner, a control valve in the supply line, a thermostatic shut-off valve in the supply line upstream from the control valve, means for supplying fuel to the pilot burner including a by-pass conduit connected into the supply line upstream from the thermostatic valve and leading to the control valve and a single conduit leading from the control valve to the pilot burner, a starter valve between the control valve and the pilot burner normally open for the flow of fuel to the pilot burner from the control valve, a thermally controlled shut-off valve in the supply line positioned upstream from the by-pass conduit and controlled by the heat of the pilot flame, an auxiliary conduit connecting into the supply line upstream from the thermally controlled shut-off valve and connecting into the starter valve, said starter valve having passage means for connecting the auxiliary conduit with the said single conduit, a valve member in the starter valve normally closing said passage, and means operable to shift said valve member to open said passage for the supply of fuel to the pilot burner when the thermally controlled valve is closed.

ERVIN H. MUELLER.
